UNITED STATES PATENT OFFICE.

JOHN GEORGE SOWERBY, OF GATESHEAD-ON-TYNE, COUNTY OF DURHAM, ENGLAND.

APPARATUS USED IN FIRE-POLISHING GLASSWARE.

SPECIFICATION forming part of Letters Patent No. 357,868, dated February 15, 1887.

Application filed December 1, 1886. Serial No. 220,409. (No model.) Patented in England May 6, 1886, No. 6,150, and in Belgium June 18, 1886, No. 73,532.

To all whom it may concern:

Be it known that I, JOHN GEORGE SOWERBY, a subject of the Queen of England, residing at Gateshead-on-Tyne, in the county of Durham 5 and Kingdom of England, have invented a new and useful Improvement in Apparatus Used in Fire-Polishing Glassware, (for which I have obtained Letters Patent for the Kingdom of Belgium under the No. 73,532, date 10 of June 18, 1886, and am applying for Letters Patent in Great Britain, No. 6,150, bearing date May 6, 1886,) of which the following is a specification.

My invention relates to an improvement applied to apparatus used to hold glassware while being fire-polished—such, for example, as the ordinary “snap” or “spring”—and it consists in covering the parts of such apparatus which come in contact with the glassware 15 with asbestos, the objects of my improvement being that the apparatus may be worked cold without fear of cracking or breaking the glass, that it will enable the workman to hold articles of glassware—such as tumblers, &c.— 20 which it is impossible to hold with the ordinary snap or spring, and that it saves the extra cost of “flattening”—that is to say, polishing—the bottom of tumblers, there being no rough bottom to be flattened, as is the case 25 in tumblers made by the present method, that is stuck upon a post or punty.

The accompanying drawing is a sectional view of an ordinary snap or spring embodying my improvement.

30 A indicates the snap or spring; B, a tumbler; C, pad or covering of asbestos fixed to clip D; E, pad on plate F.

The pads of asbestos, C E, form a cushion

for the tumbler B, interposing between it and the metal of D and F, preventing its slipping, 40 as it does when resting against the metal as in ordinary snaps, and accomplishing the objects above specified.

I have not deemed it necessary to describe the construction and action of the snap, as it 45 differs from those in ordinary use only by the addition of the pads or covering C E.

The dimensions of the asbestos coverings or pads, their number, and their shape will necessarily be dependent upon the formation of 50 the snap or spring, “box,” or other appliance used, and the size and shape of the article which it is to hold during the fire-polishing thereof.

I attach the asbestos coverings or pads to 55 the snap or other analogous apparatus with copper wire, or in any convenient manner.

I do not claim, broadly, the interposition of pads or coverings of any material between the article to be fire-polished and the metal of the 60 apparatus holding it; but

What I do claim as my invention, and desire to secure by Letters Patent, is—

In a snap or spring or analogous apparatus for holding glassware while being fire-polished, the combination of pads or coverings of asbestos with those parts of the apparatus which would otherwise come in contact with the article to be fire-polished during the operation, substantially as described, for the purposes specified. 70

JOHN GEORGE SOWERBY.
